UNITED STATES PATENT OFFICE.

ANDREW SIMONS, OF GRAND HAVEN, MICHIGAN.

REFRIGERATOR.

Application filed November 25, 1921. Serial No. 517,597.

To all whom it may concern:

Be it known that I, ANDREW SIMONS, a citizen of the United States, residing at Grand Haven, in the county of Ottawa and 5 State of Michigan, have invented new and useful Improvements in Refrigerators, of which the following is a specification.

The present invention relates to structures (such as refrigerators) having chambers 10 with a partition between them having an opening therethrough; and its object is to provide improved linings for such chambers, one lining having a hollow neck formed integrally therewith and extending thereinto 15 and outwardly therefrom and affording communication between the interiors of the linings; and further, to provide such linings and neck so formed and assembled that the linings may present at their meeting point 20 an internal surface substantially nondivergent from a direct line in the neck's longitudinal direction, thus providing a lining for the structure which shall be sanitary and readily kept clean.

25 These and any other objects hereinafter appearing are attained by, and the invention finds preferable embodiment in, the structure hereinafter particularly described in the body of this specification and illustrated 30 by the accompanying drawings, in which:—

Figure 1 is a sectional view of a portion of a structure of the character referred to, as a refrigerator, taken on a vertical plane corresponding to line 1—1 of Figures 2, 3 35 and 4;

Figure 2 is a top plan view of the bottom wall of the lining for the upper chamber seen in Figure 1;

Figure 3 is a sectional view of said lining 40 taken on a horizontal plane corresponding to line 3—3 of Figure 1;

Figure 4 is a sectional view of said structure and its lining taken on a horizontal plane corresponding to line 4—4 of Figure 45 1; and

Figure 5 is a sectional view similar to Figure 1, but showing a modified construction.

Refrigerators and the like commonly have 50 two chambers with air passages through the partition which separates such chambers, the upper chamber containing the ice and the lower chamber containing the provisions and the like. These chambers are commonly 55 provided with linings extending through

such passages. Water from the melting ice is likely to fall from the ice chamber into the provision chamber, unless means be provided to prevent it from so doing.

In the views, the refrigerator 1 has a 60 frame 2 with a door opening indicated at 3 (Fig. 2) and comprising walls enclosing the upper or ice chamber 5 and lower or provision chamber 6 with the horizontally extending partition 7 between such chambers, this partition having an opening 8 therethrough. The upper chamber 5 has a lining 9 of suitable material, such as the metallic "porcelained" sheets commonly employed for lining refrigerators. The bottom 70 wall 10 of this lining extends integrally, first upwardly or inwardly at 11 and then downwardly or outwardly at 12 to form a hollow neck 13 which neck extends, thus integral with the lining 9 inwardly into the 75 interior of said lining and outwardly into the opening 8. A second lining 14 of material similar to the lining 9 is provided for the lower or ice chamber 6, and has an upwardly outwardly extending hollow neck 15, 80 one of said necks, 13 or 15, extending into the other.

It will be seen that the reverse bend at 11, 12 of the bottom of the upper lining 9 forms a dam which prevents water in the upper 85 lining from flowing into the lower lining.

In order to provide a lining which shall be sanitary and readily kept clean, the outer or lower portion of the neck 13 of the upper lining 9 is expanded in cross section at 16 90 to receive the upper end of the neck 15 of the lining 14 of the lower chamber. By this construction the assembled linings present at their meeting point an internal surface substantially non-divergent from a 95 direct line in the longitudinal direction of the assembled necks 13, 15. A drain pipe from the upper or ice chamber is shown at 17.

In Figure 5, a collar 18 connecting the 100 linings of the upper and lower chambers is shown. This collar has expanded end portions 19 and 20 receiving respectively the neck 13¹ of the upper lining 9¹ and the neck 15¹ of the lower lining 14¹. The linings 105 9¹ and 14¹ being preferably porcelained on their inner surfaces, the collar 18 is preferably galvanized iron or the like. By forming the upper lining 9¹ with the short neck 13¹ which is not expanded at its lower end 110

as is the neck 13 at 16 seen in Figure 1, such lining 9¹ is more readily formed integrally with its neck.

Hitherto it has been difficult to form a 5 porcelained lining for the upper chamber with a dam surrounding its passage to the lower chamber, for the reason that the operation of connecting the upper and lower linings is liable to crack the porcelain. But 10 inasmuch as in my construction the linings are connected by a slip joint at their necks, this danger is eliminated. This slip joint construction also permits the linings to be connected although the frame portions supporting their bottoms respectively may be at 15 varying distances apart.

The invention being intended to be pointed out in the claims, is not to be limited to or by details of construction of the particular 20 embodiment thereof illustrated by the drawings or hereinbefore described.

I claim:

1. In a structure of the character described having two chambers with a partition 25 between them having an opening therethrough; a lining for one chamber, one of whose walls extends integrally first inwardly and then outwardly to form a hollow neck extending inwardly into the space enclosed 30 by said lining and outwardly into said opening, said neck having an outer end portion expanded in cross section; a second lining for the other chamber having an outwardly extending hollow neck extending into said 35 expanded end portion of the first mentioned lining's neck.

2. In a structure of the character de-

scribed having two chambers with a partition between them having an opening therethrough; a lining for one chamber, one of 40 whose walls extends integrally first inwardly and then outwardly to form a hollow neck extending inwardly into the space enclosed by said lining; a second lining for the other chamber having an outwardly extending 45 hollow neck, connected to the neck of the first mentioned lining.

3. In a structure of the character described having two chambers with a partition between them having an opening therethrough; 50 a porcelained lining for one chamber, one of whose walls extends integrally first inwardly and then outwardly to form a hollow neck extending inwardly into the space enclosed by said lining; a second lining for 55 the other chamber having an outwardly extending hollow neck, connected to the neck of the first mentioned lining.

4. In a structure of the character described having two chambers with a partition between them having an opening therethrough; 60 a lining for one chamber, one of whose walls extends integrally first inwardly and then outwardly to form a hollow neck extending inwardly into the space enclosed by said lining; a second lining for the other chamber having an outwardly extending hollow neck; a collar having its end portions expanded in 65 cross section, said end portions receiving the said necks respectively.

In testimony whereof I have hereunto set my hand at Grand Rapids, Michigan, this 19th day of November, 1921.

ANDREW SIMONS.
